UNITED STATES PATENT OFFICE

WILLIAM J. MAHONEY, OF NEW YORK, N. Y.

AMUSEMENT APPARATUS

Application filed February 3, 1930. Serial No. 425,621.

This invention relates generally to the class of amusement apparatus, and has particular reference to a musical instrument operable by the feet of a person while dancing, and more especially a plurality of note bars or note actuating elements combining to constitute a platform upon which a theatrical artist is adapted to dance and at the same time play his own accompaniment for the dance.

Broadly, the invention comprehends a musical dancing platform which is in the nature of a xylophone of sufficient size to permit the artist to dance thereon and sound the various note bars by means of taps or hammers suitably carried by the feet.

Obviously, if a single bar were used for each note, it would of necessity have to be made of such an extreme length in proportion to a width which would accommodate the feet of the dancer, that the over-all area would preclude the practical use of the platform in theatrical work, due to the difficulties of transportation and to the limited off-stage storage space in the theatres. Hence, the present invention aims to provide a musical dancing platform in the nature of a xylophone, in which each note consists of three similar note bars arranged in side by side relation and capable of jointly or severally emitting the same tone when struck, whereby sufficient foot space is afforded the dancer without rendering the platform unduly bulky.

As a further object, the invention contemplates means for mounting and supporting the note bars so as to afford the proper stability thereto without detracting from the tone value of the bars.

A further feature of the invention resides in the provision of rest portions interspersing certain of the note bars, to afford rest spaces upon which the dancer may alight or stand at intervals.

The invention further embodies in an apparatus of the character set forth, a construc-

tion which may be readily and accurately assembled and disassembled at the expense of a minimum of time and labor.

As a still further object, the invention includes in an apparatus of the character described, tilt guard means which functions to prevent undue tilting or canting of the note bars in event the dancer alights on the projecting extremities of the note bars.

With the above recited and other objects in view, reference is had to the following description and accompanying drawings, in which there is exhibited one example or embodiment of the invention, while the claims define the actual scope of the same.

In the drawings:

Figure 1 is a plan view of the platform.

Figure 2 is a side view thereof.

Figure 3 is an end view of the same.

Figure 4 is an enlarged fragmentary longitudinal sectional view therethrough taken approximately on the line indicated at 4—4 in Figure 1.

Figure 5 is a transverse sectional view therethrough taken approximately on the line indicated at 5—5.

Figure 6 is a perspective view illustrating the foot of the dancer equipped with means for striking the note bars.

Referring to the drawings by characters of reference, the platform consists of a plurality of rows of note bars 10, preferably constructed of hard wood, and the note bars are arranged in groups or sets which are graded as to their length so as to produce when struck a definite tone value. As illustrated, each group or set contains three note bars, but, obviously, any desired number may be included in each group or set, it being understood that the individual note bars of one group or set will produce when struck either jointly or severally one tone value. One row, designated generally by the reference character A, represents the whole tones or full notes of the musical scale, while the

other row, designated generally by the reference character B, represents the half tones or notes. In practice, the note bars 10 are supported or superimposed upon longitudinal pairs of beams 11 with a yieldable cushion 12 of felt padding or the like interposed between the upper surface of the beams and the under side of the note bars. Transverse beams 13 connect each pair of longitudinal beams 11, and the longitudinal and transverse beams are supported by an angle iron frame 14. The note bars are held in side by side relation against displacement by means of longitudinally extending cables 15 which extend through apertures in the note bars 10, one end of the cables being formed with eyes 16 through which a transverse anchoring rod 17 is engaged. The anchored ends are fixedly secured by a passage through apertures 18 in an end rail 18 which is bolted or otherwise secured to the cross beams 13. The opposite ends of the cables are attached to eye bolts 19 which extend through an end rail 20 and which have threadedly engaged thereover a nut 21, by virtue of which the proper tension may be exerted on the cables. The majority of the note bars are spaced apart from each other by means of felt washers 22 or their equivalent, and the remaining note bars are spaced apart by screw hooks 23 which are covered with a rubber tubing 24 or its equivalent, the screw hooks engaging over the cables to retain the same against deflection. The row of half tones or notes B is subdivided between certain sets of groups, and these spaces have interposed therein rest platforms 25 which are secured by screws or other fastening devices 26 to exterior laterally projecting rails 27 attached to the longitudinal beams 11 and extending throughout the length of the beam and to a center rail 28. The rails 27 and 28 are provided on their upper surfaces with yieldable pads or cushions 29, which pads or cushions have their upper surfaces spaced below the under faces of the note bars 10. The cushioned or padded rails 27 and 28 underlie the opposite ends or extremities of the note bars and function as tilt guards which only come into play in event the note bars are unduly tilted or canted.

A resonator 30 is provided for each note bar and is of substantially tubular formation having a closed lower end 31 and an open upper end 32 which is disposed medially of each note bar directly below the concaved medial portion 33 of the note bar. The resonators are graduated or vary in length proportionately with the groups or sets of note bars, and said resonators are suitably supported in any desired manner. As illustrated, the resonator supporting means consists of a pair of spaced parallel metal straps 34, between which the upper ends of the resonators are arranged and to which they are riveted as at

35 or otherwise attached. The extremities 36 of the straps are bent into substantially inverted U-shape and are designed to engage over the end rails 18. Preferably, the straps 34 are divided intermediate their ends and removably secured together in overlapped relation by thumb nuts and bolts 37. This permits the resonators and their supporting means to be readily detached from the frame of the platform when packing the same for shipment.

The angle iron frame is supported by divergent end legs 38 which are joined at their upper ends by a bight 39 carrying lugs 40 which are designed to be attached to the angle iron frame 14 by thumb bolts 41 or the like. The divergent end legs 38 are braced by angle iron angle braces 42 and cross angle iron braces 43. The end legs 38 are further braced longitudinally by angle iron angle braces 44, one terminal of each of which is detachably associated with the frame 14 by thumb bolts 45. The frame 14 is centrally braced by intermediate legs 46 which are detachably associated with the frame by bolts 47, and said intermediate legs are further braced by angle iron angle braces 48 which are detachably connected at one end with the frame 14 by bolts 49.

In use, the artist or dancer is equipped with, carries or has attached to his shoes, taps or hammers for the purpose of striking in succession the various note bars of the platform as he executes a dance thereon, to play a musical composition as an accompaniment for the dance. As illustrated in Figure 6 of the drawings, the foot C of the dancer or artist carries a hammer or striking device D, the shank E of which is attached to an elastic band F, so that the head of the hammer protrudes beyond the foot and the shank extends angularly across the same.

What is claimed is:

1. A musical instrument to be played upon by the feet of a dancer while dancing thereupon, including a supporting structure, a plurality of sets of tuned sounding bars carried by said supporting structure, the sounding bars of each set arranged in side by side relation and adapted to jointly or severally produce the same tone and the elements of the different sets adapted to produce a different tone.

2. A musical device including means for yieldably supporting in a common plane, a plurality of sound producing elements consisting of groups of note bars, the bars of each group arranged in side by side relation and having the same tone value and the groups having relatively different tone values and said elements mounted to support a dancer while dancing and playing on said elements, said supporting means including guard means disposed out of said common plane for limiting the tilting of said note bars.

3. In an amusement apparatus of the character set forth, a musical dancing platform including longitudinally extending spaced beams having cushioned upper surfaces, a plurality of transversely disposed note bars supported thereon serving as a platform to support a dancer while dancing upon and playing a musical composition on said note bars and means spaced from and underlying the protruding ends of the note bars for limiting the tilting action of the same.

4. In an amusement device, the combination of a musical instrument including tone producing elements, means for supporting said elements whereby they may be directly danced upon by a dancer and means carried by the feet of the dancer, for striking said elements while dancing directly thereupon whereby to play a musical composition coincident with the dance.

5. A musical amusement device including a plurality of sound producing elements, supporting means yieldably mounting said elements in a common plane to serve as a platform upon which a dancer is adapted to directly dance and play in unison a musical composition, the ends of said elements extending beyond the supporting means and subterposed guard means disposed below said projecting ends of said elements for limiting the tilting of the same as and for the purpose specified.

6. A musical instrument to be played upon by the feet of a dancer comprising a supporting structure, a framework carried by said supporting structure and provided with horizontally disposed tuned sounding bars to support a dancer.

7. A musical instrument to be played upon by the feet of a dancer comprising a supporting structure, a framework carried by said supporting structure and provided with horizontally disposed tuned sounding bars to support a dancer and beater means carried by the feet of the dancer.

8. An amusement device including a continuous row of sound producing elements, an adjoining interrupted row of sound producing elements, supporting means upon which the rows are mounted to produce a dancing platform and minor platforms interspersed with the elements of said interrupted row to provide rest surfaces.

9. An amusement device including a plurality of sound producing elements, supporting means across which the elements are extended to produce a dancing platform, assembling means by which said elements are maintained in side by side relation and anchoring means by which said assembling means are attached to the support.

10. An amusement device including a plurality of sound producing elements, supporting means across which the elements are extended to produce a dancing platform, as-

sembling means by which said elements are maintained in side by side relation, anchoring means by which said assembling means are attached to the support, means for anchoring the extremities of the assembling means upon the supporting means and other means carried by the supporting means engaging the assembling means to prevent deflection.

Signed at New York in the county of New York and State of New York this 31st day of January A. D. 1930.
